UNITED STATES PATENT OFFICE.

WILLIAM P. GIBSON, OF NEW YORK, N. Y.

AUTOMATIC STOP MECHANISM FOR ELEVATORS.

SPECIFICATION forming part of Letters Patent No. 412,328, dated October 8, 1889.

Application filed December 31, 1888. Serial No. 294,997. (No model.)

To all whom it may concern:

Be it known that I, WILLIAM P. GIBSON, a citizen of the United States, residing at New York, county of New York, and State of New York, have invented certain new and useful Improvements in Automatic Stop Mechanisms for Elevators, fully described and represented in the following specification and the accompanying drawings, forming a part of 10 the same.

This invention relates to improvements in safety stop mechanisms for elevators for automatically arresting the elevator-car at its upper or lower limit of movement when, 15 through carelessness or from any other cause, the elevator-conductor has failed to manipulate the hand-rope or other connection to properly operate the valve or other stopping mechanism of the elevator to cause the 20 movement of the car to be arrested at these points.

It is the object of the present invention to provide a stop mechanism of this character of such construction that its operations will be certain, reliable, and effective, which shall be capable of adjustment, so as to be rendered operative within any desired distance of the limit of movement of the elevator-car, and which shall accomplish the arrest of the 30 car at its upper or lower limit of movement easily, gradually, and without sudden jar.

To this end the invention consists, briefly, in providing the shaft carrying the sheave of the hoisting-cable of the elevator-car 35 throughout a portion of its length with screw-threads, at each end of which screw-threaded portion of said shaft is mounted a stationary nut, forming an abutment, with which engages at the proper time during the 40 movement of the elevator-car a traveling nut, also mounted upon said shaft between said stationary nuts, and connected to a barrel loosely mounted upon said shaft and connected to a sheave, also loose upon the shaft 45 and inclosing said screw-threaded portion of said shaft. Around the sheave thus connected to the barrel there passes a rope, which may be the ordinary hand-rope, and which is connected to the valve or other 50 stopping and starting mechanism in such manner as to stop the car at the top and bottom of the shaft, according to the direction in which the rope is moved. The several

devices are so constructed and arranged and so timed in their operations that during the greater part of the upward or downward movement of the elevator-car they will remain inoperative, so as not to interfere with the movement of the car; but when the elevator-car has come within a certain distance 60 of its limit of movement in either direction, the traveling nut connected to the barrel will engage with one or the other of the stationary nuts upon the shaft, and communicate the rotary movement of said shaft to said barrel and also to the sheave of the rope, and thus cause said rope to travel in the direction of the car's movement, and this movement will continue until the rope has operated the valve or other mechanism of the elevator to stop the car.

For the purposes of adjustment, so as to render the mechanism operative within desired distances of the limits of movement of the elevator-car, the stationary nuts upon the screw-threaded shaft are provided with lock-nuts, hereinafter referred to, by which, when said stationary nuts have been adjusted to desired positions, they may be locked therein and prevented from movement.

As the construction and operation of the stop mechanism constituting the present invention can be best understood from an illustration and a detailed description of an organization embodying the same, all further 85 preliminary description will be omitted and such detailed description be given in connection with the accompanying drawings, in which is illustrated so much of the mechanism of an ordinary elevator as is necessary 90 for an understanding of the invention, and in which—

Figure 1 is a front elevation of an elevator-car, its hoisting-cable, and valve-operating hand-rope and their sheaves and connections. Fig. 2 is a longitudinal section, upon an enlarged scale, of the stop mechanism of the present invention; and Fig. 3 is a cross-section of the same, taken on the line 3 of Fig. 2.

Referring to Fig. 1, it will be understood that A represents an elevator-car of the ordinary form, connected to the upper side of which is the usual hoisting-cable B, passing over a sheave C at the top of the elevator-shaft. The sheave C is fast upon a shaft D,

journaled in suitable bearings at the top of the elevator-shaft. The shaft D has also mounted loosely upon it a second sheave E, around which passes a rope F. This rope F 5 may be the ordinary hand-rope for controlling the elevator, as illustrated in the present case; or where the valve or other stopping and starting mechanism is operated from the car by other connections than a rope this 10 rope F may be provided in addition to such connections, and may pass through or outside the car. The hand-rope, as shown in the present case, passes through the elevator-car in convenient position to be grasped 15 by the hand of the conductor, as shown by dotted lines in Fig. 1, and also passes over a guide-pulley a and thence downward to the connections for operating the stopping and starting mechanism, to which it is connected 20 in the usual manner. The sheave E forms one end of a barrel H, inclosing a portion of the shaft D. That portion of the shaft D inclosed within the barrel H is screw-threaded and carries at or near each end stationary 25 nuts g h. Between the nuts g and h the shaft D has loosely mounted upon it a traveling nut i, capable of movement during the rotation of said shaft along the same between the nuts g and h, as hereinafter described. 30 The traveling nut i is provided with a projecting end j, which enters and fits loosely within a longitudinal recess k, formed in the barrel H. During the rotation of the shaft D the traveling nut i will, by reason of its 35 connection with the loosely-mounted barrel H in the manner described, travel along said shaft toward one or the other of the nuts g h, according to the direction of movement of the car, with which nut it will engage when 40 the car reaches the limit of its movement. In order to provide for the ready engagement of the traveling nut i with the nuts g h, each of said nuts is provided upon its engaging-surface with oppositely-arranged shoulders l, 45 as best shown in Fig. 2. The nuts g and h are in addition provided with lock-nuts m, by which they are securely locked and held in position upon the shaft D.

The operation of the mechanism which has 50 been described is as follows: Let it be assumed that the car A is in the position shown in Fig. 1 and is moving upward. As the upward movement of the car continues the shaft D will be revolved and with it the nuts 55 g and h, the loosely-mounted barrel H remaining stationary and the traveling nut i traveling along the shaft D toward the nut g, being guided in this movement by its connection with the barrel H. When the nut 60 i has reached the nut g, it will engage therewith. When the nuts i and g are thus brought into engagement, the nut i will be caused to revolve with the shaft D and will communicate the rotary movement of said 65 shaft to the barrel H and sheave E, said sheave revolving in the same direction as the shaft D and drawing upward upon the hand-

rope F. This revolution of the sheave E will continue until it has drawn upward sufficiently upon the hand-rope F to stop the 70 car. The operation of the different parts of the stop mechanism is so timed that the movement of the car will be arrested in an easy and gradual manner and free from jar and within the limit of its upward movement. When the car is descending, the operation will be reversed, the nut i during the rotation of the shaft D in the opposite direction traveling along said shaft and engaging with the nut h at its opposite end. When 80 the nuts i and h are thus brought into engagement, the sheave E will then revolve in a direction contrary to that just described and move the hand-rope F downward to stop the car. 85

The nuts g and h may be adjusted along the shaft D at any desired distance from each other and be locked in their positions by their lock-nuts m.

The abutments for the nut i will preferably be formed by nuts g h, as shown; but where adjustment is not required the abutments may be fixed upon the shaft D, or the abutments may be either fixed or adjustable upon the barrel. 90

When the car has been stopped at the limit of its movement in either direction, the rope F may be moved in the same direction to start the car, as such movement, instead of drawing the nut i against the stationary nut, 100 will turn the nut i so as to back it away from the stationary nut. 95

What I claim is—

1. The combination, with an elevator-car, its hoisting-cable, and the sheave over which said cable passes at the top of the shaft, of a threaded shaft D, provided with abutments and fixed to said sheave, a sheave E and barrel H, turning freely upon said shaft, a traveling nut i, working upon said threaded shaft between the abutments and connected to said barrel to lock it and the sheave E to the shaft when it engages with either abutment, and a stopping-rope F, passing around said sheave E, substantially as described. 105
2. The combination, with an elevator-car, its hoisting-cable, and the sheave over which said cable passes at the top of the shaft, of a threaded shaft D, fixed to said sheave, a sheave E and barrel H, turning freely upon 110 said shaft, a traveling nut i, working upon said threaded shaft between adjustable abutments and connected to said barrel to lock it and the sheave E to the shaft when it engages with either abutment, and a stopping-rope F, passing around said sheave E, substantially as described. 115

In testimony whereof I have hereunto set my hand in the presence of two subscribing witnesses.
